SELF-LOCKING STRUCTURE

Benjamin Louis Leeper, Kingsport, Tenn.

Application December 17, 1947, Serial No. 792,188

1 Claim. (Cl. 211—137)

1

This invention relates to self-locking structures and, particularly, to knock down structures made principally from sheet-like elements so constructed and arranged that they may be readily assembled without the use of additional fastening means and will form stable self-sustaining structures.

It is an object of this invention to provide a locking means for knock down structures whereby the application of weight to the parts of the structure will result in forcing the parts more tightly together and increasing the stability thereof.

It is another object of this invention to provide such a structure consisting of basic units that may be altered in size or extent without the use of tools or auxiliary fastening means.

Other objects and advantages will appear as the description proceeds with reference to the accompanying drawings, in which:

Fig. 1 is a perspective view of a display stand constructed in accordance with the principles of this invention;

Fig. 2 is a vertical sectional view taken substantially along line 2—2 of Fig. 1 and looking in the direction of the arrows;

Fig. 3 is an exploded view of the parts constituting the structure of Fig. 1;

Fig. 4 is a perspective view of a wheeled "parts bin" as commonly employed in factories or the like and also embodying the principles of the present invention;

Fig. 5 is a sectional view taken along the line 5—5 of Fig. 4;

Fig. 6 is a perspective view of the manner in which this invention may be embodied in a doll house or other construction toys;

Fig. 7 is a perspective view of a table constructed in accordance with the principles of this invention; and

Fig. 8 is a sectional view thereof taken along the line 8—8 of Fig. 7.

Fig. 1 illustrates a display stand commonly known in the trade as a "float" or "gondola," used in stores to support a plurality of articles for display. This type of device is usually placed in the aisles on the floor, and it is necessary that such a structure be relatively rigid to avoid collapse under the weight of articles placed thereon and to avoid upsetting or collapsing in the event of collision. The unit illustrated comprises a base member having a supporting portion made up of elements 1 and 2 and on which a platform or shelf structure 3 is preferably permanently mounted. The shelf member 3 is provided in its upper surface with a groove 4. The groove 4 extends downwardly from the upper surface of the shelf 3 a substantial distance, but, being a "groove", does not extend entirely through the shelf 3. As illustrated in Fig. 3, the groove 4 consists of a longitudinal portion 5 and a pair of transverse intersecting portions 6,

2

all of equal depth, and the ends of which terminate short of the edges of the member 3. A supporting or spacing structure 7 comprises a plurality of sheet-like elements 8 and 9 in which the element 8 is provided with a pair of upwardly facing notches 10 and the elements 9 are provided with downwardly facing notches 11. The notches 10 and 11 are so dimensioned as to snugly embrace the portions of the other element below the notch therein whereby the elements 8 and 9 may be assembled, in a well known manner to provide a cruciform structure having its upper and lower edges lying substantially in the same plane. The lengths of the elements 8 and 9 are substantially equal to the lengths of the portions 5 and 6 of the groove 4, and the said groove is of a width substantially equal to the thickness of the elements 8 and 9 whereby the cruciform structure may be placed in the groove 4 with its lower edges projecting into said grooves and below the upper surface of the member 3, as clearly shown in Fig. 2. A second shelf or supporting member 12 is provided in its lower surface with a groove 14 identical in shape and size to the groove 4 in the member 3 whereby it may be placed upon the supporting structure 7 and receive the upper edges thereof within the said groove and be frictionally held thereby against lateral displacement.

30 The upper surface of the member 12 is provided with a groove 13 which may be similar in all respects to the groove 4. A second supporting structure 14, constructed and assembled in the same manner as the structure 7, is positioned by the groove 13 to support a third member 15 having a groove 13' in its lower surface in the same manner as the member 12 is supported by the structure 7.

40 In the construction illustrated in Figs. 1 to 3, successive shelf members 12 and 15 are smaller than the one upon which they are supported whereby the completed assembly forms a generally pyramid-shaped structure and the shelf portions constitute supports for articles of merchandise to display the same in an attractive manner. It will be apparent that the grooves 13 and 13' must be of lesser longitudinal and lateral dimensions than the groove 4 since the entire structure progressively decreases in width as the height is increased.

45 The laterally extending portions 6 of the groove 4 and the elements 9 of the supporting structure 7 impart great lateral rigidity to the assembly and insure against the parts becoming separated or tilted due to a concentration of weight near an edge of any of the shelf members and that an increase in the total weight supported by the assembly will result in forcing the parts into tighter engagement to thereby firmly lock the parts together. Such a structure may be bodily shifted along the floor by lateral pressure on any

55 60

of the shelf members without danger of dislodging the parts or collapsing the structure.

The elements described may be provided in any number desired whereby the user may assemble only so much of the structure as is needed for a particular display and spare elements may be available to increase the height of the structure when the occasion demands. To this end the base structure comprising elements 1 and 2 provides a storage space 19 beneath the lowermost shelf 3 whereby extra or spare parts 16, shown by dotted lines in Fig. 2, may be retained. If desired the side members 2 may be provided with bayonet slots 17 at their inner surfaces, and cross members or slats 18 may be positioned with their ends in the said slots to provide a support for the spare parts 16.

Figs. 4 and 5 illustrate another form the invention may take. In this form a base member 20 is provided with casters or the like 21. The said base member has a groove in its upper surface to receive a supporting and partitioning structure 22. The base member 20 is preferably additionally provided with upstanding side members 23 permanently attached thereto whereby the supporting structure 22 defines with the base member a plurality of bins or compartments. In this construction it is desirable that the vertical edges of the supporting structure 22 extend to the outermost boundaries of the shelf members to provide maximum capacity within the bins or compartments. The groove in the upper surface of the base member 20 preferably terminates short of the edges of the base member in the manner illustrated in Fig. 5. The upper edges of the supporting structure 22 are received in a groove in the lower surface of an intermediate shelf 24 which is also provided with upstanding sides 23 and a groove in its upper surface identical with that in the base member 20. Clearly, additional intermediate shelves 24 and supporting structures 22 may be provided to extend the height of the bin structure to any desired elevation, and the assembly may be changed in height and capacity as the occasion demands. If desired, certain of the intermediate shelf members may be provided with a groove to receive supporting structures having a greater or lesser number of transverse elements to thereby increase or decrease the number of bins at that level. The top shelf member 25 is shown as being devoid of a grooved upper surface, which is a preferred form of construction; however, it may be a duplicate of the intermediate shelf members since the groove would not interfere with the placing thereon of articles to be transported. Likewise, if there is no need for the uppermost shelf member 25, it may be omitted entirely with the intermediate supporting member 22 providing open top bins on the intermediate shelf 24.

Fig. 6 illustrates another manner in which the invention can be employed. In this embodiment a doll house is provided with a permanent base 30 and upstanding walls 31 permanently attached thereto. The first floor partitions 32, the member 33, and the second floor partitions 34 may be constructed in accordance with the principles of this invention in a manner that will be obvious to those skilled in the art, whereby a variety of different interiors may be provided for the doll house. Clearly the principles of this invention could also be employed in other types of construction toys.

Figs. 7 and 8 illustrate a still further manner in which this invention may be employed. This

embodiment is a tier table having a base structure 40 comprising elements 41 and 42 assembled in a manner similar to the supporting structures of the above described embodiments. The base structure 40 supports a lowermost tier 43 and is preferably permanently attached thereto whereby the entire table may be lifted and moved by grasping the edges of the tier 43. Secondary and tertiary tiers 44 and 45 are each supported on the tier therebelow by supporting structures 46 and 47, similar in construction to the structures described heretofore but having their vertical edges so shaped as to provide an outline of pleasing shape. It will be evident that the upper and lower edges of the supporting structures must necessarily be of substantial length to provide necessary stability. The upper and lower edges of the supporting structures 46 and 47 are frictionally received in appropriately shaped grooves 48 in the respective tier members. Clearly, the design of the table can be altered or the number of tiers can be varied from time to time within the scope of the present invention.

The embodiments described herein all include the same inventive concept, that is, a series of superimposed shelf-like members spaced apart by supporting structures having edges frictionally received in grooves in the respective members whereby a stable knock down structure is provided and in which the supporting structures occupy a very small portion of the superficial area of the shelf-like members, thus affording a highly efficient use of the materials employed; and a structure in which greater loads act to lock the parts more securely together.

The invention is not to be limited to the embodiments described, but is contemplated to include all embodiments falling fairly within the scope of the appended claim.

40 I claim:

A structure comprising a lower member having crossed intersecting grooves in its upper surface, a removable second member having crossed intersecting grooves in its lower surface, and spacing means consisting of interlocking elements having edge portions seated in the grooves in said lower member and other edge portions seated in the grooves in said second member, said edge portions being the same length as the grooves in which they are seated whereby to support said second member in fixed spaced relation to said lower member, said spacing means comprising a relatively thin sheet-like element for each of said intersecting grooves and arranged to define separate laterally open compartments.

BENJAMIN LOUIS LEEPER.
